(57) CLAIM

The ornamental design for a Christmas tree collar, as shown and described.

DESCRIPTION

FIG. 1 is a front, right, top perspective view of a Christmas tree collar, showing my new design;

FIG. 2 is a rear, left, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged perspective view of an encircled portion labeled, "9," in FIG. 1;

FIG. 10 is an enlarged rear elevational view of an encircled portion labeled, "10," in FIG. 4;

FIG. 11 is an enlarged left side elevational view of an encircled portion labeled, "11," in FIG. 5; and,

FIG. 12 is an enlarged top plan view of an encircled portion labeled, "12," in FIG. 7.

The dashed broken lines in the figures are for the purposes of illustrating portions of the Christmas tree collar and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.
